UNITED STATES PATENT OFFICE.

ROBERT G. SEALS AND EDWARD N. C. KUNTZ, OF ST. LOUIS, MISSOURI.

DESIGN FOR AN AUTOMOBILE FRONT END DECORATION.

Application filed January 23, 1928. Serial No. 25,003. Term of patent 7 years.

To all whom it may concern:

Be it known that ROBERT G. SEALS and EDWARD N. C. KUNTZ, both citizens of the United States, residing in the city of St. Louis and State of Missouri, have invented the new, original, and ornamental Design for an Automobile Front End Decoration, of which the following is a specification, reference being had to the accompanying drawings, forming a part hereof.

In the drawings, Figure 1 is a front eleva-

tion of the automobile front end decoration showing our new design. Fig. 2 is a top plan view of the same.

We claim:

The ornamental design for an automobile front end decoration as shown.

In testimony whereof we have hereunto affixed our signatures.

ROBERT G. SEALS.
EDWARD N. C. KUNTZ.
